UNITED STATES PATENT OFFICE

2,631,034

ENDLESS COIL MAGAZINE AND CONTAINER

William Crawford Eddy, Michigan City, Ind., assignor to Television Associates, Inc., Michigan City, Ind., a corporation of Illinois

Application December 14, 1949, Serial No. 132,895

6 Claims. (Cl. 271—2.18)

1

My invention relates to an improved magazine containing an endless coil of film and to the container portion thereof. The magazine of the present invention is particularly suitable for use with the compression type film reel disclosed and claimed in my patent application S. N. 132,896, filed December 14, 1949, entitled Compression Type Endless Film Reel.

One of the principal problems associated with endless film coils arises out of the difficulty of handling these coils. While the complete film magazine, including the film guiding rollers, can be used for storage and shipment, the cost of the magazine is very great and the film guiding rollers serve no useful purpose except during the time the film is actually in operation. This difficulty is particularly acute in the case of mechanisms intended for home use where the expense of a library of complete film magazines is prohibitive.

In accordance with the present invention the film coil is stored and shipped in a simple container of cardboard or like material. When it is desired to use the film, the container or box is bodily placed on a suitable compression type film reel. The box incorporates elements operative to hold the film in predetermined position to receive the film guide members of the compression type film reel so that no hand manipulation of the film is required. Consequently the film reel is available for use with any film in the library.

It is therefore a general object of the present invention to provide a magazine for endless film coils that does not include film guiding rollers and a container for use therewith.

A further object of the present invention is to provide a magazine for endless film coils that may be received on a compression type reel without hand manipulation and a container for use therewith.

Another object of the present invention is to provide a shipping container for endless type film coils.

Yet another object of the present invention is to provide a simple, rugged, light weight, and inexpensive container for endless film coils that protects the same against mechanical damage and forms a complete enclosure about the film coil to prevent the entrance of moisture, tropical fungus, or other deteriorating agents.

Still another object of the present invention is to provide a container for endless film coils that does not hold the film in any substantial degree of flexure to the end that no permanent set is imparted to any point on the film.

The novel features which I believe to be characteristic of my invention are set forth with particularity in the appended claims. My invention itself, however, both as to its organization and mode of operation, together with further objects

2

and advantages thereof, may best be understood by reference to the following description taken in connection with the accompanying drawings, in which:

5 Figure 1 is a view in perspective of a film container constructed in accordance with one form of the present invention with the film coil in place;

Figure 2 is a view like Figure 1 with the cover of the container folded back;

Figure 3 is a top plan view of a complete film shipping container constructed in accordance with the present invention;

Figure 4 is a developed view of the container of Figures 1 and 2;

Figure 5 is a side elevational view of the container of Figures 1, 2 and 4 in place in a compression type film reel;

Figure 6 is a view in perspective of the container of Figures 1 and 2 seated in the compression type film reel and in position for closure of the film reel;

Figure 7 is a perspective view of an alternative embodiment of the container of the present invention; and,

Figure 8 is a fragmentary perspective view showing how the center post of the container of Figure 7 secures the leaving portion of the film in place.

Referring now to Figures 1 and 2, there is shown at 10 an endless coil of film. As shown, the inner periphery of the coil extends up in the leaving or issuing portion 10a which passes outside the container 12 to form a loop 10b. The end of the loop 10b enters the container to form the entering or take-up portion 10c which becomes the outer periphery of the film coil.

The container 12 is of cardboard or similar material. It has a substantially rectangular bottom 12a, Figures 2 and 4, surrounded by four sides, 12b, 12c, 12d, and 12e, which are folded up as shown in Figure 2 to define a box. Tabs 12f are provided to receive glue and anchor the sides in an upright position.

45 The side 12c of the container extends beyond the thickness of the container as shown at Figure 4. This defines the top 12g when folded along line 12h which is the edge between side 12c and top 12g. A crease 12i is provided to facilitate folding the top when the container is in place on the film reel.

50 The side 12d is cut short at edge 12j to define an aperture when folded up. This aperture receives the entering portion of the film coil 10 as shown clearly in Figures 1 and 2. Since the tangent to the outer periphery of the coil is parallel to the side 12e at the point the entering portion of the film meets the coil, the aperture defined by side 12d is properly oriented to receive the film without twist or bend.

55 In the embodiment of Figures 1 to 4, the box

has a slot in the side 12e. This slot is indicated at 12k and extends in a direction nearly parallel to the bottom 10a. The slot may be readily cut with a knife or scissors and snugly receives the leaving portion of the film 10a.

Since the slot 12k snugly receives the film 10a, the film is held in position when the top 12g is folded back to the position shown in Figure 1. The slot is placed near the center of the side 12e so that as the portion 10a of the film is held by the slot, that portion of the film is held in spaced relation with respect to the inner periphery of the film coil 10. As will be further described hereafter, this positions the film to receive the compression type film reel without further manipulation of the film.

The box may be conveniently secured in the closed position by a sealing tape 14, Figure 1, or other suitable means.

When the film containing box of Figures 1, 2 and 4 is shipped or otherwise subjected to mechanical shock and vibration, it may be placed in a container such as that shown in Figure 3. As shown, this container has a rectangular bottom 16 surrounded by four sides 18a, 18b, 18c, and 18d. The bottom and the sides 18b, 18c and 18d are formed to receive the film box snugly as shown. The side 18a is in spaced relation with the side 12e of the film box to define a space 20 in conjunction therewith. This space receives the film loop 10b that lies outside the confines of the box 12.

The box 12 is held in predetermined space relation with the side 18a of the shipping container by the spacer 20. This spacer may be a block of light wood or, preferably, is formed by folding a piece of cardboard to fit snugly in the available space and thereby prevent relative movement of the box 12 and the shipping container.

The shipping container has a top 22 formed like the bottom 16 and shown broken away in the view of Figure 3.

It will be observed that when the film is in the box 12 and the shipping container shown in Figure 3, it is protected against mechanical shock and vibration as well as the ingress of dampness and other agents that might promote deterioration. Moreover, the film is held in a coil 10 having the desired degree of tightness and an external loop 10b suitable for threading through the head of a magnetic recorder or reproducer, the stylus mechanism of a mechanical recorder, or reproducer or the gate mechanism of a motion picture camera or projector.

A further feature of the box 12 resides in the ease with which it may be inserted in a compression type film reel for operation. This is shown in Figures 5 and 6 which show the box and film inserted in a compression type film reel of the type shown and claimed in my copending patent application, S. N. 132,896, filed December 14, 1949, entitled Compression Type Endless Film Reel.

As shown in Figures 5 and 6, the compression type film reel has a rectangular bottom plate 24 upon which the box 12 rests. Three sides 26a, 26b, and 26c extend upwardly from this bottom to define a snug seat in which the box 12 fits. The rear side 26b is hinged at 28 and carries the top 30.

The top 30 is defined by a pair of spaced plates 32 and 34, the latter being below the former when the top is in the closed position shown in Figure 5. The plate 32 has a pair of opposed depending skirt portions 32a that mate with the upper edges

of the sides 26a and 26c when the top is in the closed position of Figure 5. The plate 32 is also bent down to define the curved surface 32b and the side-defining skirt 32c. When the top 30 is in closed position the side 32c overlies the side 12d of the box 12. This completes the closure about the box and holds it firmly in position. An upstanding tab 27 with an aperture 27a extends upwardly from the bottom 24 of the film reel. This registers with the handle 25 formed on the side 32c of the top and with the dimple 25a which extends outwardly from the surface of the side. When the cover 30 is closed, the dimple 25a snaps into the opening 27a to secure it releasably in the closed position.

A central guide roller 34 and a pair of spaced film coil guide rollers 36 and 38 depend from the plates 32 and 34. When the top is closed, these rollers are in their closely spaced or retracted positions shown in Figure 6. They accordingly fit easily within the confines of the film coil 10. When the cover is thus closed, the operating arm 40 is rocked to the operative position where the rollers 34, 36, and 38 expand to grip the film coil 10 snugly and guide the film for winding.

The mechanism for expanding the rollers 34, 36, and 38 in response to the movement of arm 40 is shown and described in my copending patent application S. N. 132,896, filed December 14, 1949, entitled Compression Type Endless Film Reel.

When the cover 30 is closed, the roller 36 must pass between the leaving portion of the film, 10a, and the inner periphery of the coil 10. Since the slot 12k holds this portion of the film in spaced relation with the inner periphery of the coil, the roller fits in position without rearranging or holding the film in any way. This is a great practical advantage because the film 40 is very difficult to handle and cannot be manipulated by inexperienced persons without risk of unwinding the whole film and converting it to a hopeless tangle.

When the cover 30 is snapped closed, the portion 10c of the film is withdrawn from the slot 12k to permit free withdrawal of the film in response to the demands of the film using device.

While the box 12 is on the compression type reel, the film is held in spaced relation to the bottom of the box by the ribs 42 that extend upwardly from the bottom 24 of the reel. The bottom of the box is apertured at 44 to receive these ribs. Since the coil 10 rests on the smooth ribs and in the rough bottom of the box, the frictional opposition to coil rotation is only the relatively small opposition associated with the smooth ribs.

The compression type film reel is preferably mounted on a suitable stand 46, Figure 5. This stand is not shown in Figure 6.

In Figure 5 the film loop 10b is shown passing through the gate mechanism of a motion picture projector, shown generally at 48. It will, of course, be understood that this is only illustrative and that the film may be threaded through other film using devices, such as a motion picture camera, the head of a magnetic recorder or reproducer, or the stylus of a mechanical recorder or reproducer. As the film is withdrawn from the inner periphery of the coil 10, the coil is rotated to take up the film on the outer periphery of the coil, thus taking up the slack as it is released from the film using device.

Figures 7 and 8 show a modification of the box 75 12. In this modification the side 12e is notched

out at 12k' to define an opening that freely receives the leaving portion of the film. However, this portion of the film is held in spaced relation to the inner periphery of the film coil 10 by the upstanding post 50 which is formed by cutting out a centrally disposed U-shaped portion of bottom 12a' and bending it up as shown. The post 50 has a pair of oppositely directed inwardly extending slots 50a.

As shown in Figure 8, the oppositely directed slots 50a receive the opposite edges of the leaving portion 18a of the film. The triangular tabs on the side of the post 50 flex outwardly to hold the film securely in place without substantially flexing the film. Since the post is disposed centrally of the container, the leaving portion of the film, 18a, is held in spaced relation relative to the inner periphery of the coil and permits the cover 30 of the compression type film reel to be swung into position without manipulating the film. The portion 18a of the film can then be withdrawn from the slots 50a to permit free film motion in response to the demands of the associated film using device.

The form of the box 12 shown in Figure 7 also differs from the form in Figures 1 to 6 in having a pair of film retaining flaps 52 and an extra scored portion 54 for folding the top 12g'.

In this specification I have identified the portion 18a of the film as the "leaving portion" because the film is normally withdrawn from the center of the coil 10. Similarly, the portion 18c of the film is designated as the "entering" portion, since the film is normally wound on the outside of the coil.

In the present specification I have used the term "magazine" to denote the combination of the film box 12 or 12' and the film contained therein.

While I have shown and described specific embodiments of the present invention, it will of course be understood that I do not wish to be limited thereto and that by the appended claims I intend to cover all modifications and alternative constructions falling within the true spirit and scope of my invention.

What I claim as new and desire to secure by Letters Patent of the United States is:

1. A container for an endless film coil having a loop connecting the inner and outer peripheries of the coil and extending outside the confines of the container, comprising a box adapted to receive the coil having an aperture adjacent one corner to receive the entering portion of the coil, and a film retainer attached to the box operative to secure the leaving portion of the coil in spaced relation with the inner periphery of the coil whereby a space for accommodating a guide member is provided between said leaving portion and said inner periphery, facilitating insertion of said container into a reel provided with such a guide member.

2. A container for an endless film coil having a loop connecting the inner and outer peripheries of the coil and extending outside the confines of the container, comprising a box adapted to receive the coil having an aperture adjacent one corner to receive the entering portion of the coil, and a post extending upward from the bottom of the box near the center thereof adapted releasably to receive the leaving portion of the coil to secure it in spaced relation with the inner periphery of the coil whereby a space for accommodating a guide member is provided between said leaving portion and said inner periphery, facilitating in-

sertion of said container into a reel provided with such a guide member.

5 3. A container for an endless film coil having a loop connecting the inner and outer peripheries of the coil and extending outside the confines of the container, comprising a box having a bottom and side walls adapted to receive the coil and having an aperture to receive the entering portion of the coil, one side of the box having a slot nearly parallel with the bottom of the box and extending inwardly from one edge thereof, the slot being adapted to receive the leaving portion of the coil snugly to secure the same in spaced relation with the inner periphery of the coil whereby a space for accommodating a guide member is provided between said leaving portion and said inner periphery, facilitating insertion of said container into a reel provided with such a guide member.

15 4. A container for an endless film coil having a loop connecting the inner and outer peripheries of the coil and extending outside the confines of the container, comprising a box of cardboard or the like having a bottom and side walls adapted to receive the coil, one side wall having an aperture to receive the entering portion of the coil, a portion of the bottom defining a centrally disposed upstanding post with spaced oppositely directed inwardly extending slots adapted to secure the leaving portion of the film releasably in spaced relation with the inner periphery of the coil whereby a space for accommodating a guide member is provided between said leaving portion and said inner periphery, facilitating insertion of 20 35 said container into a reel provided with such a guide member.

5. A film magazine comprising a box having a bottom and side walls surrounding the bottom, an endless film coil in the box, said coil having a loop connecting the inner and outer peripheries of the coil and extending outside the confines of the magazine, the box defining two apertures, one oriented substantially parallel to the film in the coil and the other oriented substantially transverse to the film in the coil, the entering portion of the coil passing through said one aperture and the leaving portion passing through said other aperture, the box defining elements operative to hold the leaving portion of the film in spaced relation with the inner periphery of the coil.

40 45 6. A film magazine comprising a box having a bottom and side walls surrounding the bottom, an endless film coil received in the box, said coil having a loop connecting the inner and outer peripheries of the coil and extending outside the confines of the magazine, the sides having an aperture substantially parallel to the film in the coil and a slot nearly parallel to the bottom extending inwardly from one edge, the entering portion of the coil passing through the aperture and the leaving portion of the coil being received snugly in the slot releasably to secure the leaving portion in spaced relation with the inner periphery of the coil.
